UNITED STATES PATENT OFFICE.

CHARLES M. GIDANSKI, OF NEW YORK, N. Y.

RAIL-SUPPORTING STRUCTURE.

1,110,124.

Specification of Letters Patent.

Patented Sept. 8, 1914.

Application filed May 12, 1913. Serial No. 767,113.

To all whom it may concern:

Be it known that I, CHARLES M. GIDANSKI, a citizen of the United States, residing at the city of New York, in the borough of Brooklyn and State of New York, have invented certain new and useful Improvements in Rail-Supporting Structures, of which the following is a full, clear, and exact description.

10 This invention relates to improvements in rail supporting structures.

One of the objects of my invention is to provide means for substantially preventing deterioration of the rails due to corruga-
15 tion.

According to the present construction of urban and subway lines the ties are embedded for their entire length in a foundation or road bed of concrete or some other 20 substantially unyielding substance upon which the rails are directly laid. As a car or train passes over the rail the wheel load is distributed over a relatively small area of the top surface of the rail. This stress 25 is transmitted through the rail to the foundation, which will not yield as the stress at the base of the rail is distributed over a comparatively large area. The deformation caused by the load will therefore, occur al-
30 most entirely within the rail which should be of sufficient strength to sustain this strain without exceeding its elastic limit. It has been found, however, that frequently the portion of the top surface of the rail which 35 sustains the wheel load for a short interval of time will be strained beyond its elastic limit, resulting in the formation of a shallow indentation, the displaced or extruded portion of the surface forming a ridge in
40 front of the indentation. Upon the frequent passing of wheels under heavy loads over the rails the indentation will become deeper and the ridge more pronounced resulting finally in corrugation of the rails to such an extent
45 that the track and rolling stock will be affected upon the passing of a heavily loaded car over the rails.

My invention therefore resides in the provision of means whereby the deformation caused by the wheel load will occur in the supporting structure rather than in the rail itself and I obtain this result by providing a yielding supporting structure, interposed

between the rails and rigid foundation which structure is deflected under the wheel load 55 but within its elastic limit.

In the accompanying drawing I have illustrated an embodiment of my invention, but it is not my intention to be limited to the specific form shown, but only by the scope 60 of the claims appended hereto.

In the drawings, Figure 1 is a plan view showing my improved form of supporting structure portions of the pavement being removed. Figs. 2, 3 and 4 are sections on 65 the lines 2-2, 3-3, 4-4, respectively.

In the drawings 1 designates the foundation or road bed made of concrete or some other substantially non-yielding material which is customarily used in the construction 70 of road beds in urban and subway lines. Spaced apart at definite intervals are the ties 2 provided with offset ends 3. These ties with the exception of their offset ends are embedded in the concrete foundation 75 so that they will be rigidly held against displacement in any direction.

Track rails 4-4 connected by the tie rods 5 are secured to the offset ends 3 by fastening means 6 of any well known form which 80 engage over the upper surfaces of the flanges or bases of the rails and are secured to the offset ends thereby holding the rails against displacement. Recesses 7 are provided in the concrete foundation surrounding 85 the cantaliver or offset ends 3 which are therefore free to be deflected vertically by the wheel load. Shallow grooves or trenches 8 connected with the recesses 7 are formed in the concrete foundation directly 90 beneath the base or flange of the track rails, so that the base of the rail does not rest directly upon the concrete foundation at any point. The load is therefore carried entirely by the offset ends of the ties. The ties as 95 shown consist of steel I-beams which are of sufficient strength to withstand the cantaliver and shearing stresses due to the wheel load without straining beyond their elastic limit, yet yielding sufficiently to permit deflection of the offset or cantaliver ends under the stress of the wheel load, thus counter-acting any tendency toward deformation in the rail itself.

It is not my intention to limit this invention to steel ties as it is obvious that any

other structural material which will fulfil the same requirements may be used.

The grooves 8 and the recesses 7 are filled with an adhesive pitch or cement 10 which surrounds the offset ends of the ties and the flanges of the rails, although the latter construction is not essential and the bottom surface of the rail may rest directly upon the top surface of the pitch. The pitch used 10 should have sufficient elasticity so that upon the deflection of the rails and the offset ends of the ties, it will be compressed but will resume its original position after the rails and the offset ends resume their original position. The pitch is not intended to aid in supporting the rails, but is merely employed to protect the rails from corrosion which might otherwise be caused by water or frost.

As shown the paving blocks 11 used to 20 pave the street between the rails rest upon a sand cushion 12 while the remaining portion of the road or street may be paved with asphalt or the like, the particular form of pavement used forming no part of my invention. The spaces between these blocks and the rails are filled with an impervious 25 filler which protects the webs of the rails and the ends of the tie rods from corrosion or deterioration due to other causes and further prevents water seeping down through the space between the rails and blocks.

It is obvious that the rails, in the construction described, are supported entirely by the ties and do not rest at any point upon the 35 unyielding foundation. Upon the passage of the train or car over the rails, each wheel load will be transmitted to the rail and then to the offset ends of the ties which will be deflected, the amount of deflection being 40 just sufficient to cushion the rails, so that the deformation in the top surface of the rail caused by the compression of the rail between the wheel load and the more or less unyielding foundation will be avoided and 45 the deterioration due to corrugation prevented. When the load is removed from the rails, the offset ends of the ties will resume their original positions, as they are of sufficient strength to sustain the load without 50 straining beyond their elastic limit.

This invention also has a particular adaptation to rail joints, frogs or other special work where the top surfaces of the abutting ends of the rails are worn and 55 dished, such dishing being due to a large extent to the same cause as is the corrugation in the top surface of the rail. By yieldingly supporting or suspending the joint, frogs or other special work, the tendency for 60 the load as it passes from one rail to another to wear a depression in one of the rails adjacent the joint, will be eliminated as the supporting ties will take up the strain.

While I have shown ties for sustaining 65 the strain of the wheel load, yet it is appar-

ent that the invention is not limited to this specific form and any yieldingly mounted structure interposed between the rail and the substantially rigid foundation is within the purview of the invention. Nor is it my 79 intention to limit myself to the specific concrete foundation illustrated and the phrase "substantially unyielding road bed" is intended to cover any foundation which does not yield sufficiently to counteract the tendency for the rails to corrugate. 75

Having described my invention, I claim:

1. A rail tie having cantaliver ends substantially parallel to but out of alignment with the main portion of the tie. 80
2. A rail tie comprising an I-beam having a cantaliver end substantially parallel to but out of alignment with the main portion of the tie. 85
3. In combination, a substantially unyielding road bed, a tie rigidly supported by said road bed, said tie having an offset end free for deflection under load and rails forming a rail joint which is supported directly by said offset end. 90

4. In combination, a substantially unyielding road bed, a tie having an offset end, said tie being rigidly supported by the foundation, the offset end being free for deflection under load and a rail mounted on said end. 95

5. In combination, a substantially unyielding road bed, track rails and supporting ties therefor, said ties being embedded in said road bed, said road bed being formed with recesses surrounding the ends of the ties, 100 said track rails being supported on said ends out of contact with said road bed.

6. In combination, a substantially unyielding road bed, a tie, said tie being rigidly supported by the foundation and having a 105 free end, and a track rail mounted on the free end of the tie, said tie being of sufficient strength to sustain the wheel load without straining beyond its elastic limit.

7. In combination, a substantially unyielding road bed, a tie comprising an I-beam having an offset end, said I-beam being rigidly supported by the foundation and its offset end being free to deflect with the load, and a rail mounted on said offset end. 110

8. In combination, a substantially unyielding road bed, track rails, supporting ties therefor, said ties being embedded in the road bed, said road bed having recesses surrounding the ends of the ties and grooves in 120 the surface of the road bed beneath said rail, and elastic waterproof filling in said grooves and recesses.

9. In combination, a substantially unyielding road bed, a track rail having a bead, 125 and means interposed between said bead and said road bed for yieldingly supporting said bead.

10. In combination, a substantially unyielding road bed, track rails, supporting 130

ties therefor rigidly supported by said road bed, said road bed having recesses surrounding the ends of the ties and an elastic waterproof filler in said recesses.

5 11. In combination, a substantially unyielding supporting structure and a resilient member mounted on said supporting structure, said member having an offset end out

of contact with said structure and a rail bearing directly on said offset end. 10

In witness whereof, I subscribe my signature, in the presence of two witnesses.

CHARLES M. GIDANSKI.
